MECHANICS TEST MITT FOR INTERNAL COMBUSTION ENGINES

Emil V. Gualano, Los Angeles, Calif.

Application November 5, 1957, Serial No. 701,694

2 Claims. (Cl. 2—161)

This invention relates to a mechanic's test mitt for handling "hot" or live wires particularly around motor vehicle engines, and in particular a mitt formed to the curvature of a hand and having a relatively large hand receiving opening in the inner end and provided with gripping surfaces between the thumb and forefinger and also having a flat surface on the back of the thumb to facilitate picking up tools and the like.

The purpose of this invention is to provide a protective mitten for mechanics and the like that is formed of relatively heavy material and shaped to the natural position of the hand so that it may readily be used for gripping tools, wires and the like without flexing the body portion of the mitten.

Various types of comparatively thin gloves formed of rubber and other insulating materials have been provided for electricians but for currents from coils producing sparks such as in motor vehicle engines comparatively heavy insulation is required not only at the finger tips but all around the hand. With this thought in mind this invention contemplates a mitt in the form of a shield that is preformed to the position in which it is used and into which a hand may readily be inserted and from which the hand may readily be removed.

The object of this invention is, therefore, to provide means for constructing a mechanic's mitt whereby the glove may be of relatively heavy material and at the same time provide comfort and easy manipulation of the gripping elements.

Another object of the invention is to provide a preformed mitt of insulating material in which wire gripping surfaces are provided between the thumb and forefinger.

A further object of the invention is to provide a comparatively heavy mitt to protect the hands of mechanics and the like which is of a simple and economical construction.

With these and other objects and advantages in view the invention embodies a mitt having a body portion formed to correspond to the shape of a hand with a thumb stall having a flat outer surface and with gripping ridges provided across the inner surface of the thumb stall and inner surface of part of the mitt in which the forefinger is positioned.

Other features and advantages of the invention will appear from the following description taken in connection with the drawings wherein:

Fig. 1 is a perspective view of the mitten looking toward the edge on which the thumb stall is positioned;

Fig. 2 is a longitudinal section through the mitt in the position as illustrated in Fig. 1;

Fig. 3 is a plan view of the mitt looking toward the palm portion thereof;

Fig. 4 is a cross-section through the thumb stall taken on line 4—4 of Fig. 2; and

Fig. 5 is a cross-section through the finger section of the mitt taken on line 5—5 of Fig. 2.

Referring now to the drawings wherein like reference characters denote corresponding parts, the improved pre-

2

formed protective mitt of this invention shows a finger section 10 with a thumb stall 11 and the finger section is provided with a wall 12 (Fig. 5) corresponding with the palm of the hand and an outer wall 13 is providing

5 a covering for the back of the hand.

The body portion of the mitt is provided with an opening 14 through which a hand may be inserted in the mitt and a projection 15 may be provided at one side of the opening to protect the last joint of a thumb. The opening 10 14 has an arcuate portion 14a which extends up the outer wall 13 of the mitt so that when the mitt is positioned on the hand the wall 13 extends just over the knuckles.

The outer part or back of the thumb stall 11 is provided with a flat surface 16 that extends from the tip 17 (Fig. 3) to a point 18 corresponding with the base of the thumb. This flat surface facilitates picking up tools and the like. The inner surface of the thumb stall is formed with a crease or ridge 19 dividing the inner surface into an outer part 20 and an inner part 21. The thumb stall may also be provided with slight projections 22 and 23 to correspond with the knuckles or joints of the thumb.

The inner palm surface 12 is formed with projecting 25 ridges 24 and 25, as shown in Fig. 2, and also a connecting ridge 26 (Fig. 3) which provides a valley or recess in which a wire may be gripped between the inner surface of the thumb and the part of the finger portion of the mitt corresponding with the forefinger. The finger 30 section of the mitt is provided with an inner wall 27, as shown in Fig. 5, and the inner projecting ridge 25 merges into a crease 28, as shown in Fig. 1.

With the parts arranged in this manner, the hand may readily be slipped into the mitt when it is desired to 35 work around the electrical connections of a motor vehicle engine and particularly for testing the spark, and the wires or tools may readily be gripped between the ridges on the surface of the forefinger portion of the body part of that mitten and the coating surfaces of the thumb 40 whereby the wires may be positively held without danger of current passing through the hand.

The back portion of the mitt is cut away, as shown at 45 14a, providing a wide opening in the end of the mitt to facilitate entry and release or withdrawal of the hand.

As previously stated, general use is for testing spark 50 efficiency of automotive, aircraft and marine gasoline engines or any internal combustion engine equipped with an ignition system.

The mechanic applies the mitt to the hand to avoid 55 high tension electrical ignition shock when testing coil or spark plug wires while the motor is in operation.

The user may maneuver the ignition wire to test and 60 examine the color of spark, quicker and more efficiently without exposing himself to a high tension electrical ignition shock.

It will be noted that the body of the mitt is curved at the palm and back of fingers to provide a natural hand grasping position.

60 It will also be understood that although the mitten is shown for use on a right hand it may also be provided for the left hand.

It will be understood that modifications may be made 65 in the design and arrangement of the parts without departing from the spirit of the invention. What is claimed as new and desired to be secured by Letters Patent is:

1. A preformed insulated mitt for mechanics and the like comprising a body portion, a thumb stall and a finger portion, said thumb stall and finger portion being disposed in close adjacency to receive a wire therebetween and grip the same, the body portion having an extension to cover the wrist of the wearer adjacent the

palm, a projection on one side of the body portion adjacent the thumb stall to protect the last joint of the thumb of the wearer, the body portion being cut away on the back whereby the plane of the hand opening for the mitt is disposed at an obtuse angle with respect to the longitudinal axis of the mitt so that when the mitt is disposed on a horizontal surface the angular plane of the opening facilitates entry and removal of the hand.

2. An insulated mitt according to claim 1 including 10 flat portion on the back side of the thumb stall.
